J. W. WHITLOCK.
COIN-ACTUATED MECHANISM.
APPLICATION FILED AUG. 14, 1905.

UNITED STATES PATENT OFFICE.

JOHN W. WHITLOCK, OF RISING SUN, INDIANA.

COIN-ACTUATED MECHANISM.

No. 825,167.

Specification of Letters Patent.

Patented July 3, 1906.

Application filed August 14, 1905. Serial No. 274,182.

To all whom it may concern.

Be it known that I, JOHN W. WHITLOCK, a citizen of the United States, residing at Rising Sun, in the county of Ohio and State of Indiana, have invented certain new and useful Improvements in Coin-Actuated Mechanisms, of which the following is a specification.

The purpose of this invention is to prevent the electric contacts of circuits closed by prescribed coins from corroding by sparking and to keep said contacts clean, so as to insure the closing of the circuit each time a coin comes into proper position, which is essential to the operativeness and reliability of mechanisms of the type aforesaid.

The invention also provides for the automatic operation of the machine in the event of a number of coins being deposited therein at one time or in rapid succession, thereby avoiding the annoyance incident to waiting for the completion of each operation of the machine before the next coin may be deposited to insure a repetition, as well as adding to the earnings of the machine, since a player may become interested in the automatic feature of the machine in rendering service for each and every coin placed therein and is more likely to deposit a number of coins at one time than if required to place them singly one at the end of each operation.

The invention further contemplates combining with the pneumatic action and as a part thereof two bellows, the one for actuating the cut-off and coin-release and the other cooperating with the said first-mentioned bellows to effect a resetting of the parts preliminary to the next operation, when another coin drops into position to again close the circuit.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of a coin-actuated mechanism embodying the invention, the component parts being illustrated in operative relation disassociated from supporting means. Fig. 2 is a horizontal section of

a portion of the mechanism on the line $z z$ of Fig. 1, illustrating the two bellows in full lines. Fig. 3 is a detail view showing the relation of the parts when the coin cut-off and release actuating bellows is compressed. Fig. 4 is a detail view of the parts shown in Fig. 3, illustrating the relation of the coöperating elements when the resetting-bellows is collapsed and the coin cut-off and release actuating bellows expanded. Fig. 5 is a detail perspective view of a portion of the resetting-bellows, the valve controlled thereby for regulating the vent of the pneumatic action governing the coin cut-off and release actuating bellows. Fig. 6 is a vertical transverse section of the coinway on the line $z z$ of Fig. 1 looking to the right, showing the parts on a larger scale. Fig. 7 is a detail view in elevation of the coin-actuated mechanism. Fig. 8 is a sectional detail view of a valve on a larger scale.

Corresponding and like parts are referred to in the following description and indicated in all the views of the drawings by the same reference characters.

The invention is particularly designed as an improvement on the mechanism disclosed in Patent No. 658,134, granted to me September 18, 1900, for self-playing musical instrument, although it is contemplated to adapt it to coin-actuated mechanisms of any structural type employing a pneumatic action or susceptible of use in connection with bellows or like pneumatic contrivances.

In the accompanying drawings the numeral 1 indicates a tracker-bar; 2, a musical or note sheet for coöperation therewith in the well-known manner; 3, a pneumatic action consisting of a box and valved compartments; 4, an electric motor; 5, a vacuum-creating device, such as a bellows, for withdrawing the air from the exhaust-chest of the pneumatic action, and 6 a coinway. These parts are substantially the same as disclosed in my patent herein referred to.

The circuit including the electric motor 4 comprises wires 7, 8, 9, and 10 and contacts 11 and 12, the latter being fixed and the former movable. A latch-spring 13 normally exerts a pressure upon the movable contact 11 to hold it in a predetermined position. The contact 11 has its upper portion reduced to form a shoulder 14, which arrests the descent of a prescribed coin C, by means of which the circuit is closed and the mechanism started. The circuit-closer is located at

any convenient position in the length of the coinway, so as to receive a regularly-deposited coin of determinate value for operating the machine. When a coin of prearranged value is received between the contacts 11 and 12, the circuit is completed and the motor 4 actuated and the bellows or other type of air-pumping mechanism operated so as to exhaust the air from the chamber 15 of the action-case 3 to admit of proper operation of the machine. A tube 16 connects the exhaust-chest 15 with the bellows or air-exhausting device 5. The current-generator is indicated at 17 and may be a battery or dynamo, to the poles of which the respective wires 9 and 10 are electrically connected. Starting from the generator 17 the circuit is through wire 9 to contact 12, coin C, contact 11, wires 8 and 7, motor 4, and through wire 10 back to the generator 17.

To prevent sparking upon breaking the circuit by the discharge of the coin C, the following means have been devised: A bar 18 is slidably mounted upon a suitable support 19 between guides 20, which preferably consist of screws let into said support. The bar 18 is arranged to clear the contact 12 and is pointed at its active end, as indicated at 21, said point being arranged to engage with an edge of the coin C above a horizontal line passed through its center. As a result of this arrangement of the bar 18, a forward movement thereof toward the movable contact 11 will serve to press the coin 13 downward and at the same time to move the contact 11 away from the contact 12 to effect a discharge of the coin C when the same clears the shoulder 14. As the bar 18 advances and effects a discharge of the coin C it also effects a separation of said coin from those immediately above in the coinway 6, forming a support therefor and obstructing their passage through the machine. A blade 22 is electrically connected with the wire 9 and contact 12 and normally exerts a pressure upon the bar 18 and is in electric connection therewith. A second blade 23 is electrically connected with the wires 7 and 8 and is normally spaced from the bar 18. A projection 24, forming a part of or attached to the bar 18, is beveled at its front end and is adapted to make electrical connection with the blade 23 upon the forward movement of the bar 18, thereby establishing and completing the circuit through the blades 22 and 23 and the bar 18 preliminary to braking of the circuit by discharge of the coin C from between the contacts 11 and 12. Hence no spark is produced at the instant the coin passes from between the said contacts 11 and 12. The blades 22 and 23 are metallic springs, and the bar 18 and projecting portion 24 are likewise of metal. The projection 24 is of some length to maintain frictional contact with the blade 23 during the sliding movement of the

bar 18, thereby insuring closing of the circuit until the bar 18 has nearly reached the limit of its return stroke, when the part 24 clears the blade 23 and the circuit is interrupted. The bar 18 constitutes, in effect, a cut-off and a release, since upon its forward movement it serves to support the coin above the one located between the contacts 11 and 12 and at the same time acts to effect a discharge of the latter. A link 25 connects the coin cut-off 75 and release 18 with an actuating-bellows 26, which is connected with a valve-chamber of the action-case 3 by means of a tube 27. When the bellows 26 or similar pneumatic appliance is collapsed, the bar 18 is moved forward, as indicated most clearly in Fig. 3. When the bellows 26 is expanded, the bar 18 is returned to or occupies a normal position, as indicated most clearly in Fig. 4.

In order to a clear understanding of the 85 operation of the mechanism, a brief description of the pneumatic action is deemed necessary. The box or action-case 3 is subdivided to provide an exhaust-chest 15 and a plurality of valve-chambers 28. An opening 29 is formed in the outer wall of each valve-chamber 28, and a corresponding opening 30 is provided in the partition 31, separating the exhaust-chest 15 from the valve-chambers 28. The openings 29 and 30 are 90 in coincident relation and are controlled by a valve 32, which upon its inward movement closes the opening 30 and upon its outward movement closes the opening 29. Openings 29 constitute vents and admit of the several bellows or like pneumatic contrivance exhausting or venting. When an opening 30 is uncovered and the corresponding opening 29 closed, communication is established between the selected bellows and the exhaust-chest, 95 and said bellows is collapsed or operated to effect actuation of the part connected therewith and depending upon movement thereby. A diaphragm 33 is connected to the stem 34 of each valve 32 and covers an opening in a 100 side of the exhaust-chest. A vent 35 is provided in the lower portion of each valve-stem 34 to admit of exhausting the air below the diaphragm 33. A tube 36 connects each opening of the tracker-bar 1 with an 105 opening of the action-case, coöperating with a diaphragm 33. When the opening of the tracker-bar is closed by an imperforate portion of the music or note sheet 2, the diaphragm 33 corresponding to said opening is 110 collapsed and the corresponding valve 32 is moved inward and closes the opening 30 and uncovers the corresponding opening 29, thereby permitting venting or exhaustion of the air from the bellows connected therewith. When an opening in the tracker-bar is uncovered by a perforation in the note or music sheet registering therewith, air is admitted into the tube 36 and the diaphragm 33 quickly expands and causes the valve 32 115

to uncover the opening 30, whereby the bellows is caused to collapse and is actuated so as to effect operation of the part connected therewith. The resetting-bellows 37 is connected by tube 38 with one of the valve-chambers 28 and is adapted to control a valve 39, by means of which the vent to the valve-chamber with which the bellows 26 connects is regulated. A tube 40 extends from the opening controlled by the diaphragm 33 of the valve-chamber, through which the tube 27 connects, and is adapted to be closed by the valve 39. For convenience a block 41 is provided and attached to the support 19 and has an opening 42, with which the tube 40 connects and which is adapted to be closed by the valve 39. The valve 39 consists of a plate hinged to the block 41 and normally acted upon by means of a spring 43 to press it closed. The valve 39 is held open against the tension of the spring 43 by means of a rod 44, slidably mounted in a guide 45 and connected to the resetting-bellows 37. When both bellows 26 and 37 are expanded or in normal condition, the valve 39 is unseated, so that upon closing the electric circuit to the motor by a deposited coin the bellows 26 may be collapsed or actuated to effect operation of the cut-off and release 18, as indicated most clearly in Fig. 3. When the machine has completed its operation or played a piece, an opening 46 in the note or music sheet 2 will register with an opening in the tracker-bar 1, with which the tube 26 communicates, and the diaphragm 33, covering the opening of the action-case in communication with the tube 36, will expand and move the valve 32 so as to uncover the opening 30 and admit of the air being exhausted from the bellows 37, which will withdraw the rod 44 and permit the valve 39 to close, with the result that the diaphragm 33, controlling the opening of the action-case in connection with the tube 40, is collapsed and the valve 32 moved to close the opening 30 and to uncover the vent 29, thereby permitting the bellows 26 to expand automatically and return the cut-off and release 18 to normal position. These several positions are indicated in Fig. 4. The resetting-bellows 37 is provided with a trip 47, which extends into a longitudinal slot 48 in the support 19 and is adapted to engage with a stop 49, projected from the bar 18. As the resetting-bellows reaches the limit of its movement when collapsed, the trip 47 will come in contact with the stop 49 and insure complete expansion of the bellows 26 should its spring fail or be insufficient to accomplish this result. When the bar 18 assumes its normal position, the circuit, including the motor 4, is interrupted and the air-exhausting device 5 brought to rest, with the result that the chest 15 is relieved of vacuum-pressure and the bellows 37 enabled to assume a

normal position and again unseating the valve 39.

Near the upper end of the coinway 6 is arranged a device to prevent the withdrawal of a coin after being deposited and starting the machine. This device consists of a lever 50, weighted at its lower end and provided at its upper end with a jaw 51, which is adapted to be projected across the coinway and bind a string or like connection attached to a coin with the intention of defrauding the machine. A projection 52, extended inward from the lever 50, normally obstructs the passage through the coinway, and upon depositing a coin the latter moves the projection 52 aside and automatically operates the lever 50 so as to project the jaw 51 across the coinway and effect a clamping of the string attached to the coin, thereby preventing the latter from reaching the circuit-closure, so as to effect bridging thereof to complete the circuit and effect operation of the machine. A number of coins may be placed in the machine and when deposited stand in the coinway 6. The lowermost coin closes the circuit and the motor by coming between the contacts 11 and 12, as indicated in Fig. 7, and when the bar 18 is shot forward, as indicated in Fig. 3, it separates the lowermost coin from those above and supports the latter and at the same time effects a release of said lowermost coin. When the machine has completed an operation or played a piece, the bar 18 is withdrawn in the manner herein stated and the coins in the way 6 drop automatically, and the lowermost coin is released to again complete the circuit and to automatically start the machine for the next operation. Each coin in turn automatically drops into operative position and serves to start the machine without any care or attention on the part of the person playing the machine.

Having thus described the invention, what is claimed as new is—

1. In a coin-actuated mechanism, the combination of a starting mechanism adapted to be actuated by a regularly-deposited coin, a pneumatic action, a coin cut-off and release, a pneumatic actuator therefor, a valve for controlling the operation of said pneumatic actuator for the coin cut-off and release, and a pneumatic actuator for said valve normally holding the same open and adapted to close the valve when the machine is reaching the limit of its operation to effect a return of the coin cut-off and release to a normal position and a stop of the machine through the operation of said pneumatic action.

2. In a coin-actuated mechanism, the combination of a starting mechanism including a motor and adapted to be set in motion by means of a regularly-deposited coin, a pneumatic action, a coin cut-off and release, a pneumatic actuator therefor having connection with said pneumatic action, a resetting pneu-

matic actuator, a valve for controlling the supply of exhaustion of air to the pneumatic actuator of the coin cut-off and release, means connected with the resetting pneumatic actuator for normally holding the aforesaid controlling-valve open, and actuating means between the resetting pneumatic actuator and the coin cut-off and release pneumatic actuator to insure return of the latter to normal position upon operation of said pneumatic resetting-actuator.

3. In coin-actuated mechanism, the combination of starting mechanism including a motor and adapted to be set in motion by means of a regularly-deposited coin, a pneumatic action, a coin cut-off and release, a pneumatic actuator therefor, a pneumatic resetting-actuator, a valve controlled thereby for regulating the supply or exhaust of air from the pneumatic actuator of the coin cut-off and release, positive connecting means between said coin cut-off and release and its pneumatic actuator, and a trip and stop between the pneumatic resetting-actuator and said coin cut-off and release to effect a resetting of the coin cut-off and release and pneumatic actuator after said controlling-valve has been closed.

4. In a coin-vending mechanism, the combination of an electric motor, a circuit therefore including normally separated contacts which are adapted to be electrically connected by a regularly-deposited coin, blades included in said circuit, each having electric

connection with one of said electric contacts; a coin cut-off and release normally in electrical connection with one of said blades and having a projecting portion to be brought in electrical connection with the other blade upon forward movement of said coin cut-off and release for completing the circuit through the said blades and cut-off, and operating means for said cut-off and release.

5. In combination, an electric circuit including an electric motor and contacts, said circuit adapted to be closed by means of regularly-deposited coin, blades electrically connected with each of said contacts, a coin cut-off and release normally in electric connection with one of said blades and provided with a projecting portion to make electrical connection with the other blade when said coin cut-off and release is moved forward, a pneumatic action, a pneumatic actuator for the coin cut-off and release, a valve for regulating the admission and the exhausting of air therefrom through the pneumatic action, a pneumatic actuator for said valve, and co-operating means between the coin cut-off and release and the resetting pneumatic actuator.

In testimony whereof I affix my signature in presence of two witnesses.
